SKATE GUARD

Alton C. Day, Roseland, N. J.

Application September 7, 1937, Serial No. 162,784

8 Claims. (Cl. 280—11.38)

The present invention relates to that class of appliances and accessories embodying skaters' equipment, and has more particular reference to a structurally new and novel ice skate guard 5 of the sandal-type designed to facilitate walking with skates on.

It is a matter of common knowledge that the inconvenience of attaching skates at the pond has gradually brought into vogue a now well established practice of attaching the skates at the 10 club house or sometimes at home before starting on the journey to the pleasure spot. Moreover, since it is difficult to walk on skates any appreciable distance, and as such walking would prove 15 ruinous to the skate blades, different types of shields of temporary walker treads are recommended.

As implied by the preceding paragraph, I am 20 sufficiently conversant with the general state of the prior art to appreciate that the use of ice 25 skate guards is not an original concept. In fact, I realize in making my entry into this specialized field of invention, I am confronted with protector attachments of variegated styles and forms. It 30 follows, therefore, that my principal objective is to improve upon such prior devices through the adoption and use of a structurally singular guard assembly believed comparatively unique and more 35 aptly fitted for the intended purposes.

In keeping with the underlying principles of 30 my presently adopted construction, I have found it expedient and practicable to employ a twin or dual unit assembly wherein the units are properly shaped for walking and coordinated by connecting means calculated to promote the desired 35 flexibility considered to be the cardinal improvement.

Other features and advantages will become 40 more readily apparent from the following description and accompanying drawings.

In the drawings, wherein like numerals are employed to designate like details and parts throughout the views:

Figure 1 is a side elevation of a duplex-style, 45 self-accommodating ice skate guard constructed in accordance with the principles of the present invention.

Figure 2 is a top plan view of the assembly disclosed in Figure 1.

50 Figure 3 is a central longitudinal sectional view.

Figure 4 is an end elevational view of the front- 55 al or so-called toe unit.

Figure 5 is a similar view observing the heel unit in Figure 1 in a direction from left to right.

Figure 6 is a perspective view of one of the details.

As before indicated, the guard, as a unitary assemblage, is made up primarily of a pair of complementary or companion toe and heel units 5 5 and 8, respectively, and they have common structural characteristics in that each is in the nature of a channelled or grooved sheath adequately designed to receive the blade portion of the conventional ice skate (not shown).

The unit 7 is made up of wood and includes a pair of spaced parallel longitudinal side blocks 9 adjoined in spaced parallelism along their lower edges by a cleat-like runner or tread strip 10. This arrangement provides the aforementioned 10 channel-shaped receptacle or sheath for the complementary portion of the runner or blade of the 15 skate. As a unit, this part 7 may be said to have its front end tilted forwardly and downwardly, as indicated at 11, to terminate in a pointed tip 20 12. The rear edges of the side members are curved, as at 13, to facilitate walking in snow or on yieldable frozen ground. The major portion of the bottom of said unit slants upwardly and forwardly on the approximate plane indicated at 14, where it converges toward the tip 12. At the juncture of the thus obtuse angled surfaces 13 and 14 is a rounded portion 15 forming 25 a fulcrum designed to aid rocking on the ball of the foot, so to speak, as has been found to be advisable to overcome clumsiness and inconvenience found to be evident in completely flat-faced tread-equipped devices exemplified in certain prior art structures heretofore recommended for use. Incidentally, this particular type of a 30 sheath, as indicated at 7, has been found to be expedient and practicable to facilitate driving one's automobile. This makes it possible to put the skates on at home and to drive the automobile to the skating pond or other equivalent 35 point.

Referring now to the heel sheath or unit 8, it will be observed that this has certain common characteristics in that it includes spaced parallel side blocks 16 joined together at their lower 45 ends by a jointing cleat 17 nailed or otherwise secured in place, as indicated at 18. The blocks 16 are generally approximately rectangular in form with the rear ends curved to accommodate a metal plate or shield 19 forming a closure as 50 well as an abutment for the adjacent end portion of the skate.

The two units 7 and 8 are adjoined in cooperative relationship and proper alignment through the instrumentality of metal tie straps 20. These 55

are adjustably attached at opposite ends, as indicated at the points 21, whereby to permit sufficient play to exist to allow slight relative movement of the parts 7 and 8 with respect to each other and to thus enhance the features of adaptability and to provide what is in effect a flexible walking shoe for an ice skate.

The wooden wedges 22 are secured in proper angular relation on the outer sides of the units 7 and 8 to permit anchorage thereon of the end portions 23 of the saddling or harnessing straps. Suitable straps including buckles 24 are generally employed whereby to allow the device to be satisfactorily strapped on the foot of the wearer.

15 It is thought that the description taken in connection with the drawings will enable a clear understanding of the invention to be had. Therefore, a more lengthy description is thought unnecessary.

20 While the preferred embodiment of the invention has been shown and described, it is to be understood that minor changes coming within the field of invention claimed may be resorted to if desired.

25 I claim:

1. A temporarily usable walking shoe designed for use in conjunction with an ice skate comprising a pair of relatively swingable and tiltable units for reception of the skate runner, said 30 units being in the nature of sheaths flexibly adjoined in cooperative shiftable walking relationship.

2. A skate guard of the class described comprising individual heel and toe units adapted for 35 reception of the blade of the skate, and means pivotally adjoining said units together to allow movement of one in relation to the other.

3. An ice skate guard embodying sheath means for reception of the blade of the skate, said means 40 being provided on its bottom at a predetermined point with a fulcruming rocker member to facilitate walking.

4. An ice skate guard of the class described

comprising an auxiliary walking shoe including complementary heel and toe units and tie straps adjoining adjacent ends of the units in spaced longitudinal alignment.

5. An ice skate guard of the class described 5 comprising an auxiliary walking shoe including complementary heel and toe units and tie straps adjoining adjacent ends of the units in spaced longitudinal alignment, the heel unit including spaced parallel side members and an end plate 10 constituting an abutment for the adjacent end of the skate.

6. An ice skate guard of the class described comprising an auxiliary walking shoe including complementary heel and toe units and tie straps 15 adjoining adjacent ends of the units in spaced longitudinal alignment, said toe unit being channel-shaped in cross-section and open at opposite ends, the outer frontal end being tapered and pointed, the inner rear end being curved rearwardly and upwardly and the intermediate tread portion being fashioned to provide a rocker as described.

7. A skate guard of the class described comprising a heel unit substantially rectangular in 20 side elevation, channel-shaped in cross-sectional form, having a flat bottom and a closing plate at one end constituting a skate abutment, and a bodily movable companion toe unit swingably adjoined thereto.

8. A skate guard of the class described comprising a heel unit substantially rectangular in side elevation, channel-shaped in cross-sectional form, having a flat bottom and a closing plate at one end constituting a skate abutment, a toe 35 unit movably adjoined thereto, said toe unit being channel-shaped in cross-section, longitudinally elongated, open at opposite ends, with its frontal portion inclined downwardly and the intermediate part of its basal tread portion convexed to 40 provide a fulcruming element.

ALTON C. DAY.
